UNITED STATES PATENT OFFICE.

LAURENCE A. HAWKINS, OF SCHENECTADY, NEW YORK, ASSIGNOR TO
GENERAL ELECTRIC COMPANY, A CORPORATION OF NEW YORK.

BLOCK-SIGNAL SYSTEM.

No. 844,797.

Specification of Letters Patent.

Patented Feb. 19, 1907.

Application filed July 31, 1905. Serial No. 271,871.

To all whom it may concern:

Be it known that I, LAURENCE A. HAWKINS, a citizen of the United States, residing at Schenectady, in the county of Schenectady and State of New York, have invented certain new and useful Improvements in Block-Signal Systems, of which the following is a specification.

My invention relates to block-signal systems, and particularly to systems adapted to give an indication at the entrance of each block of the condition both of that block and the following block or, in other words, to give clear, caution, and danger indications. Signals for giving these three indications have been arranged heretofore either with two arms, each adapted to assume two different positions, or with a single arm adapted to assume any one of three positions. My invention is equally applicable to both types of signals and will be illustrated and described in connection with both modifications. Two general types of systems for controlling such signals have been commonly used heretofore. In one type of system wires are extended back from each block to the signal at the entrance of the preceding block, so that each signal is controlled not only by trains in its own block, but also by trains in the following block. The second system, which has been used heretofore, employs no wires connecting adjacent signals, and the rails themselves furnish the only electrical connection. The control of one signal by a train in the following block has been obtained in this latter type of system by inserting a reversing-switch in circuit with the track-battery and connecting it to the signal of the following block and using two relays—one neutral and one polarized—for controlling conjointly the signal at the entrance of the block. The polarized and neutral armatures may be controlled by independent windings or both by the same winding.

In a former application, Serial No. 217,212, filed by me July 19, 1904, I have shown an arrangement in which a single armature accomplished the same results which have been accomplished before by means of two armatures, one neutral and one polarized. As fully explained in my former application, I accomplish this result by arranging the relay so that the armature has three different positions—an off position and an operative posi-

tion on each side of the off position. Such a relay has certain disadvantages, since the off position is less definite than in the case of an armature having only two positions.

The object of my present invention is to accomplish the same results with a single armature having only two positions. I accomplish this by controlling the track-relay not only by trains in that block and in the following block, but also by the signal which is itself controlled by the relay.

More specifically stated, my invention consists in the combination, with a signal adapted to give clear, caution, and danger indications, of a source of current connected to the rail-circuit at the exit end of the block, a reversing-switch in circuit with the source and controlled by a train on the following block, a relay connected to the rail-circuit at the entrance end of the block and controlling the signal, and means controlled by the signal for reversing the connections of the relay to the rail-circuit. As will appear later in this specification, a relay having a permanently-polarized armature would operate satisfactorily in the above system, as far as trains passing in one direction over a main line are concerned, but would not operate properly when a train ran off a block onto a siding. In order to secure proper operation under all conditions whatsoever, I so arrange the relay that it has a neutral armature in certain positions of the signal and a polarized armature in other positions.

Accordingly, one feature of my invention consists in the combination, with a signal, of a track-relay controlling the signal and having means controlled by the signal for rendering the armature of the relay polarized in one or more positions of the signal and non-polarized in another position.

My invention will be best understood by reference to the accompanying drawings, in which—

Figure 1 shows a block-signal system arranged in accordance with my invention, the signals shown being of the one-arm three-position type. Fig. 2 shows a similar arrangement applied to the control of two-arm two-position signals, and Fig. 3 shows a view of the track-relay.

Referring first to Fig. 1, T^1 , T^2 , and T^3 represent three railway-blocks electrically insulated from each other. The block T^3 is

shown occupied by a car or train t . S' , S^2 , and S^3 represent signals at the entrance to the respective blocks. These signals are adapted to give three distinct indications, corresponding to "clear," "caution," and "danger," this being accomplished by a single arm assuming three different positions, as shown. The signals are counterweighted, so as to return automatically to danger position when released by the mechanism. M' , M^2 , and M^3 represent electric motors for driving the signals from danger to caution and to clear positions. The specific construction and arrangement of the operating mechanism forms no part of my present invention; but I have illustrated an operating-circuit adapted for use with signal-operating mechanisms of the type described in Patent No. 683,397, to Herman, September 24, 1901, and I have consequently shown the signal S' provided with a clutch-magnet C' , adapted to clutch the motor to the signal and release it therefrom, and a lock-magnet L' , adapted to lock the signal at caution and clear positions. B' represents a source of current for the operating mechanism of the signal S' . R' represents the track-relay connected to the entrance end of the block T' and provided with a neutral armature r' . m' represents a magnetizing-coil adapted when energized to polarize the armature r' . A' represents an auxiliary relay controlled by the track-relay R' and by the signal S' , as will be hereinafter explained, and having four armatures, as shown, by means of which it controls the signal S' in certain positions thereof conjointly with the track-relay R' and also serves to reverse the connections of the relay R' to the rail-circuit. The rails of the block T' at the exit end of the block are connected, through the reversing-switch c^2 , controlled by the signal S^2 , to the track-battery b^2 . The signals S' , S^2 , and S^3 are operatively connected to the controlling-switches s' , s^2 , and s^3 , which may be of any suitable type, but which, for the sake of clearness, are shown with movable contacts developed on a plane surface adapted to be engaged by stationary contact-fingers, as shown. The motor-circuits are shown in heavy lines, while the circuits of the relays and the lock-magnets are shown in light lines.

The operation of the system is as follows: With a train on a block, as shown at block T^3 , the track-relay R^3 is short-circuited, and consequently drops its armature to the position shown, thereby breaking the circuit of motor, clutch-magnet, and lock-magnet and allowing the signal S^3 to be carried to danger position by its counterweight, as shown. It will be noticed that the circuit of the magnetizing-coil m^3 is open at the left-hand contact-finger of switch s^3 , so that the armature is not polarized. This condition of affairs continues as long as the train is in the block

T^3 . Whenever the train leaves the block, the short circuit will be removed from the track-relay R^3 , which will consequently draw up its armature, closing a circuit from the lower terminal of battery B^3 , through relay-armature r^3 , through the armature a^3 of auxiliary relay A^3 , to the back contact of this armature, through the switch s^3 , clutch-magnet C^3 , motor M^3 , to the upper terminal of battery B^3 . The circuit of motor and clutch is consequently closed, and the motor starts, driving the signal S^3 from danger to caution position. When caution position is reached, the conditions of the circuits will be the same as shown in the drawings for the signal S^2 . By referring to the circuits of the signal S^2 it will be seen that the circuit of the motor and clutch has been broken by the switch s^2 while the circuit of the lock-magnet L^2 has been closed. Furthermore, the circuit of the magnetizing-coil m^2 is closed, so that the armature r^2 is polarized. The polarization is in such a direction, however, as long as the signal S^3 is at "danger" that the attraction of the relay R^2 on its armature is not affected or merely somewhat increased. It will be seen that the track-batteries b' and b^2 are connected to the rail-circuit in one way with the signal at "danger" and in the opposite way with the signal at either "caution" or "clear"—that is, while the signal is passing from "danger" to "caution," or vice versa, the connections of the track-battery of the preceding block are reversed. The circuit connections of the signal S^2 remain as shown as long as a train is in block T^3 , and the signal S^3 remains at "danger." When the train passes out of this block and the signal S^3 is driven from "danger" to "caution" in the manner that has been above explained, the connections of the track-battery b^2 are reversed, thereby sending current through the relay R^2 in the opposite direction. Since the armature r^2 is now polarized, this reversal of current in the relay R^2 causes the relay to drop its armature momentarily. When the armature is dropped, a circuit is closed from the lower terminal of the battery B^2 , through the relay-armature r^2 , through the back contact of the armature, through the auxiliary relay A^2 , through the switch s^2 , to the upper terminal of battery B^2 . The auxiliary relay A^2 is consequently energized and draws up its four armatures. The two lower armatures form a reversing-switch for the track-relay R^2 , so that the direction of current through this relay-winding is again reversed, and it draws up its polarized armature r^2 practically instantaneously. The relay-armature a^2 is arranged to short-circuit the back contact of the relay armature r^2 , so as to close a maintaining-circuit for the winding of the relay A^2 . Consequently this auxiliary relay is not deenergized when the track-relay again picks up its armature. The upper armature a^2 of A^2

the auxiliary relay closes a circuit as follows: from the lower terminal of battery B^2 , through the relay-armature r^2 , through the front contact of this armature, through the relay-armature a^2 , through the front contact of this armature, through the switch s^2 , and through the clutch-coil C^2 and motor M^2 to upper terminal of battery B^2 . The motor and clutch are consequently again energized 5 and drive the signal from "caution" to "clear." The condition of the circuits at clear position is shown for signal S' . Both the track-relay R' and auxiliary relay A' maintain their armatures raised while the switch s' has broken the circuit of motor and clutch and has closed the circuit of lock-magnet L' . When a signal is thus cleared, it remains clear until a train again comes onto the block. The track-relay R' is then short-circuited, opening the circuit of the lock-magnet and allowing the signal to be carried 10 to danger position by its counterweight. It is to be further noted that the signals behind a train will be operated correctly when a train backs onto a block. For instance, if a train on block T^3 should back from block T^3 to block T^2 it would short-circuit the track-relay R^2 and allow the signal to go to "danger." This movement of the signal S^2 would 15 reverse the connections of the track-battery b' , thereby reversing the direction of current-flow through the relay-winding R' . The relay R' would consequently drop its armature and the counterweight would start the signal S' toward danger position. The signal would 20 not pass beyond or at least much beyond caution position, for as soon as the circuit of the auxiliary relay A' is broken by the switch s' at or a little beyond caution position the relay A' would drop its armature, thereby 25 again reversing the current-flow to the track-relay. The track-relay would consequently pick up its armature, closing the lock-circuit to hold the signal at caution position, or if 30 the signal has passed somewhat beyond caution position it would close the circuit of the clutch and motor to run the signal back to caution position. When caution position is 35 reached, the motor and clutch would be cut out and the lock-magnet cut in in the manner heretofore explained.

As far as the explanation given heretofore is concerned the operation would be precisely the same as described if the track-relays had permanently-polarized armatures. Such an arrangement, however, would not operate the signal ahead of the train satisfactorily when a train leaves a block by backing off it or the signals behind a train when it 45 leaves a block by running onto a siding. The reason for this is that the signal for the following block would then be at clear position, so that if a polarized relay were properly connected to respond when the following 50 signal is at danger position it would not re-

spond at all with the following signal at clear position when the train left the block by running onto a siding—that is, the signal would remain at danger position. The same thing as regards the signal ahead would happen if 55 a train backed off a block. It is in order to take care of such conditions of operation that the relay is so arranged that part of the time it is neutral and part of the time polarized. With such a relay the system will operate 60 satisfactorily, not only for trains proceeding in either direction over the main line, but also for trains leaving a block by running onto a siding. This is clear from the following considerations: When the train leaves the block, 65 removing the short circuit from the relay, the relay will pick up its armature, regardless of the position of the following signal, since the relay-armature is at that time neutral. The relay-armature remains neutral until 70 caution position is reached or nearly reached, when the circuit of the magnetizing-coil is closed, as has been heretofore explained. If the following signal is at caution or clear position, as would be the case when a train runs 75 off the block onto a siding, instead of at danger position, as would be the case when a train runs off a block onto the following block, the direction of current through the track-relay would be such that when the armature is polarized it drops the armature momentarily; but this momentary dropping of the armature closes the circuit of the auxiliary relay, reverses the connection of the track-relay to the rails, and causes it to pick 80 up its armature again instantaneously. The motor and clutch-circuit would consequently be maintained closed and the motor would drive the signal from caution to clear position. It should be noted that the contacts 85 on the signal-operated switches $s' s^2$, &c., should be so arranged that the movable contact connected to the front contact of the upper armature of the auxiliary relay will have engaged its corresponding contact-finger by the time the auxiliary relay picks up.

In Fig. 2 I have shown the same system as heretofore described applied to the control of signals adapted to give clear, caution, and danger indications by means of two two-position arms, which are known as "home" and "distant" signals, and which in the drawings are indicated by the letters H and D . In this figure, for the sake of simplicity, the clutch and lock magnets of Fig. 1 are omitted, 90 and the operating mechanism for the signals H' and D' are merely indicated by the motors M'_1 and M'_2 , respectively. This renders it possible greatly to simplify the representation of the controlling-switch s' . The operation of the system is exactly the same as has been heretofore explained and requires no further discussion.

Fig. 3 shows a suitable arrangement for the track-relay. The relay-coil is indicated at 95

R, and the neutral armature is shown at r. This armature is carried on a lever or arm E, pivoted at e and normally resting against a stop or back contact e'. The arm carries at 5 its outer end a contact f, adapted to engage a stationary contact F when the armature r is attracted by the relay-magnet. The relay-armature r is surrounded by a suitable stationary magnetizing-coil m, which when energized polarizes the relay-armature.

It will be understood that I have represented my invention diagrammatically and that in practice any suitable form of apparatus may be employed. Furthermore, 15 many variations in the circuit connections may be made without in any way altering the mode of operation. For instance, it is utterly immaterial whether the reversing-switch controlled by the auxiliary relay is in 20 circuit with the main magnet-winding of the relay or of the magnetizing-winding. Accordingly I do not desire to limit myself to the particular construction and arrangement of parts here shown, but aim in the appended 25 claims to cover all modifications which are within the scope of my invention.

What I claim as new, and desire to secure by Letters Patent of the United States, is—

1. In a block-signal system, a signal adapted to give clear, caution and danger indications, a track-relay controlling said signal, means controlling said relay and controlled by a train in the following block, and means controlling said relay and controlled by said 30 signal.

2. In a block-signal system, a signal at the entrance of a block adapted to give clear, caution and danger indications, a source of current connected to the rail-circuit of the 40 block, means controlled by a train in the following block for reversing the connection of said source to the rail-circuit, a relay connected to the rail-circuit of the block and controlling the signal, and means controlled by the signal for reversing the connections of 45 a winding of said relay.

3. In a block-signal system, a circuit comprising a source of current, the rails of the 50 block, a relay, and two reversing-switches, one of said switches being inserted in circuit between said source and the rails and the other between the rails and said relay, a signal controlled by said relay, means controlled by a train in the following block for operating the first reversing-switch, and means controlled by said signal for operating the second reversing-switch.

4. In a block-signal system, a signal at the entrance of a block adapted to give clear, 60 caution and danger indications, a track-relay controlling said signal, a source of current connected to the rail-circuit of the block, means for reversing the connections of said source when a train leaves the following 65 block, and means for reversing the connec-

tions of a winding of the relay when the relay is deenergized and the signal is at caution.

5. In a block-signal system, a signal at the entrance of a block adapted to give clear, caution and danger indications, a source of current connected to the rail-circuit of the block, a reversing-switch in circuit with said source controlled by a train in the following block, a track-relay controlling said signal, an auxiliary relay, contacts controlled by 70 said track-relay and by said signal in circuit with said auxiliary relay, and a reversing-switch in circuit with a winding of the track-relay controlled by the auxiliary relay. 75

6. In a block-signal system, a signal at the entrance of a block adapted to give clear, caution and danger indications, a source of current connected to the rail-circuit of the block, a reversing-switch in circuit with said source controlled by a train in the following 80 block, a track-relay controlling said signal, an auxiliary relay, a circuit for said auxiliary relay comprising a back contact of the track-relay and contacts controlled by the signal and closed when the signal is at caution, and 85 a reversing-switch in circuit with a winding of the track-relay and controlled by said auxiliary relay. 90

7. In a block-signal system, a signal at the entrance of a block adapted to give clear, 95 caution and danger indications, a source of current connected to the rail-circuit of the block, a reversing-switch in circuit with said source controlled by a train in the following block, a track-relay controlling said signal, an auxiliary relay, a circuit for said auxiliary relay comprising a back contact of the track-relay and contacts controlled by the signal and closed when the signal is at caution, a 100 reversing-switch in circuit with a winding of the track-relay and controlled by said auxiliary relay, and a contact controlled by said auxiliary relay adapted to short-circuit said back contact of the track-relay. 105

8. In a block-signal system, a signal at the entrance of a block adapted to give clear, caution and danger indications, a source of current connected to the rail-circuit at the exit end of the block, a switch in the connections between said source and rail-circuit 115 controlled by a train in the following block, a track-relay connected to the rail-circuit at the entrance of the block controlling said signal, an auxiliary relay controlling said signal conjointly with said track-relay in certain positions of said signal, and a circuit for said auxiliary relay including a back contact of the track-relay and contacts controlled by the signal. 120

9. In a block-signal system, a signal at the entrance of a block adapted to give clear, caution and danger indications, a source of current connected to the rail-circuit at the exit end of the block, a switch in the connections between said source and rail circuit 130

- controlled by a train in the following block, a track-relay connected to the rail-circuit at the entrance of the block controlling said signal, an auxiliary relay controlling said signal conjointly with said track-relay in certain positions of said signal, a circuit for said auxiliary relay including a back contact of the track-relay and contacts controlled by the signal, and a contact controlled by said auxiliary relay adapted to short-circuit said back contact of the track-relay.
10. In a block-signal system, a signal at the entrance of a block adapted to give clear, caution and danger indications, a source of current connected to the rail-circuit of the block, a reversing-switch in circuit with said source and controlled by a train in the following block, a track-relay having a neutral armature connected to the rail-circuit of the block and controlling said signal, and means for polarizing said armature when the signal is at caution or clear.
11. In a block-signal system, a signal at the entrance of a block adapted to give clear, caution and danger indications, a source of current connected to the rail-circuit of the block, a reversing-switch in circuit with said source and controlled by a train in the following block, a track-relay having a neutral armature connected to the rail-circuit of the block and controlling said signal, a winding adapted when energized to polarize said armature, and contacts in circuit with said winding controlled by the signal.
12. In a block-signal system, a signal at the entrance of a block adapted to give clear, caution and danger indications, a source of current connected to the rail-circuit at the exit end of the block, a reversing-switch in circuit with said source and controlled by a train in the following block, a track-relay having a neutral armature connected to the rail-circuit at the entrance of the block and controlling said signal, a winding adapted when energized to polarize said armature, and means controlled by the signal for energizing said winding when the signal is at caution or clear.
13. In a block-signal system, a circuit comprising a source of current, the rails of a block, a relay, and two reversing-switches, one of said switches being inserted in circuit between said source and the rails and the other between the rails and said relay, means controlled by a train in the following block for operating the first reversing-switch, means controlled by said signal for operating the second reversing-switch, and means controlled by the signal for rendering the armature of said relay polarized in one or more positions of said signal and non-polarized in another position.
14. In a block-signal system, a signal at the entrance of a block adapted to give clear, caution and danger indications, a track-relay controlling said signal, a source of current connected to the rail-circuit at the exit end of the block, means for reversing the connections of said source when a train leaves the following block, means for reversing the connections of a winding of the relay when the relay is deenergized and the signal is at caution, and means controlled by the signal for rendering the armature of the track-relay polarized when the signal is at caution or clear and non-polarized when the signal is at danger.
15. In a block-signal system, a signal, a track-relay controlling said signal, and means controlled by the signal for rendering the armature of said relay polarized in one or more positions of said signal and non-polarized in another position.
16. In a block-signal system, a signal, a track-relay controlling said signal, said relay having a neutral armature, a winding adapted when energized to polarize said armature, and contacts in circuit with said winding controlled by said signal, said contacts being arranged to close the circuit of said winding to polarize the relay in certain positions of said signal and to open the circuit of said winding in other positions of said signal.

In witness whereof I have hereunto set my hand this 29th day of July, 1905.

LAURENCE A. HAWKINS.
